Claims priority, application Switzerland March 28, 1952

3 Claims. (Cl. 336—70)

The present invention relates to electrical transformer and other windings of the high voltage type and particularly those in which the windings may be subjected to voltage waves having a steep front. Unless some means are provided for distributing this voltage in a somewhat equal manner between the various coils which make up the windings and particularly those which constitute the primary i. e. the high voltage side of the transformer, an extremely high stress is placed on those coils at the beginning of the primary winding which may result in a breakdown of the insulation thereon.

The pattern of voltage distribution between the various coils of the winding, i. e. the voltage gradient, is determined by their capacities and various expedients have been adopted to increase such capacities by the addition of other capacitative units thereby to improve the voltage gradient. One type of capacity unit in popular use consists of a conductive screen arranged to surround the outside of the high voltage winding and which is electrically connected to the beginning of the winding. However such screens require much space and result in constructions of undesirable shape. Moreover the edges of such screens must have high strength insulation since they carry the very high potential existing at the beginning of the primary winding, thus making it necessary to space the screens and winding far apart. The same disadvantage obtains when the additional capacity units are constituted by cylindrical metallic plates or the like imbedded in the transformer insulation or distributed throughout the length of the winding in a telescope like arrangement. That is, great difficulties arise because of the insulation requirement at the edges of the metallic insertions and because of the voltage gradients occurring due to the operational frequencies.

The object of the present invention is to provide an improved arrangement for high voltage windings such as the high voltage side of a transformer which results in a better voltage gradient in the event of steep front voltage waves. According to this inventive concept the high voltage side of the transformer is constituted by a plurality of series connected disc type coils in superposed relation and conductive and non-magnetic rings are disposed at both the inner and outer sides of the coils, the rings at each side being arranged in close superposed relation and each ring being insulated from the other rings. Preferably those rings at the inner sides of the coils overlap, i. e. capacitatively bridge such adjacent coils as are electrically connected together at their outer sides, and in a similar manner those rings at the outer sides of the coils capacitatively bridge such adjacent coils as are electrically connected together at their inner sides. Also those rings disposed at the inner and outer sides of the particular coil which constitutes the beginning of the winding are preferably connected to such coil at its point of connection to the high voltage source.

The inventive concept will be more clearly understood from the following detailed description and drawings wherein Fig. 1 is a view in central vertical section of a

portion of a transformer incorporating the invention and Fig. 2 is an electrical schematic view showing a slight modification.

With reference now to Fig. 1 wherein those portions of the transformer structure not essential to an understanding of the present invention have been omitted in the interest of simplifying the disclosure, it will be seen that the transformer is of the well known concentric winding type. The secondary or low voltage winding, sectionalized into two concentric, radially spaced coils 1a, 1b, is located adjacent to and concentric with the central core 2. Surrounding secondary windings 1a, 1b and separating the same from the high voltage primary winding 4 is a cylinder of insulation 3 of the well known laminated type made from paper. It will be observed that primary winding 4 is composed of a plurality of disc type coils 4a, 4b, 4c, 4d, 4e, and 4f arranged in superposed parallel spaced relation concentric with secondary windings 1a, 1b and that the several coils are interconnected in series, the connection between adjacent coils being located alternately at the inner and outer sides of the coils. Thus conductor 5a connects coils 4a and 4b at their outer sides, conductor 5b connects coils 4b and 4c at their inner sides, conductor 5c connects coils 4c and 4d at their outer sides, conductor 5d connects coils 4d and 4e at their inner sides and conductor 5e connects coils 4e and 4f at their outer sides. The turns which make up each coil have radial spacing therebetween but this is immaterial so far as the invention is concerned. The lead-in 6 from the high voltage source is connected to the inner side of coil 4a.

Metallic conductive and non-magnetic rings 7a, 7b, 7c and 7d are located between insulating cylinder 3 and the inner sides of the primary coils 4a-4f. These rings are each wrapped with insulating material 10 to insulate each from the other and are also arranged concentric with the axis of transformer core 2 and in close superposed relation. Preferably ring 7a overlaps, i. e. capacitatively bridges the vertical gap between the inner sides of primary coils 4a, 4b which are interconnected at their outer sides. In a similar manner, ring 7b capacitatively bridges primary coils 4c, 4d and ring 7c capacitatively bridges coils 4e, 4f.

Another group of metallic conductive mutually insulated and non-magnetic rings 8a, 8b, 8c and 8d similar to rings 7a-7d are disposed adjacent the outer sides of primary coils 4a-4f. Ring 8b capacitatively bridges the vertical gap between the outer sides of primary coils 4b, 4c which are interconnected at their inner sides. In a similar manner, ring 8c capacitatively bridges coils 4d, 4e also interconnected at their inner sides.

If desired, rings 7a-7d and 8a-8d instead of being metallic throughout may be constructed from laminated paper insulation which is then surface coated with a conductive material to bring about the desired capacity effect.

In order to obtain the desired alternate bridging effect it will be seen that the height of the several rings 7a-7d and 8a-8d is made greater than the combined height of each pair of adjacent primary coils so that abutment between adjacent rings occurs adjacent the connecting conductors 5a-5e for adjacent coils. This of course means that the uppermost inner ring 7a can be of full height but the uppermost outer ring 8a must be of half that height. Rings 7a and 8a, disposed at the inner and outer sides respectively of the uppermost coil 4a to an end terminal of which the high voltage lead 6 is connected, are also preferably interconnected by conductor 9 and are also connected to the lead 6.

It will be understood of course that the complete transformer includes other primary coils below those illustrated and that other capacitative coupling rings are associated therewith in the same manner as those already

described to the end that the rings will be substantially coextensive in height with the entire length of the primary winding.

Fig. 2 shows in schematic form a slightly different embodiment of the invention wherein the high voltage lead 6' instead of being connected to the uppermost coil 4a' is connected to an end terminal of one of the intermediate coils such as 4h' thus dividing the primary winding in two electrically parallel branches, one branch consisting of coils 4a-4h' and the other coils 4h'-4p'. Otherwise the arrangement of the low voltage winding 1a', 1b', core 2' and inner and outer auxiliary capacity rings 7a'-7g' and 8a'-8i' are the same as Fig. 1.

In conclusion it will be seen that the improved arrangement according to the invention results in a most compact construction and a most favorable voltage distribution along the entire primary winding. Moreover the voltage difference between adjacent coils at their non-connected sides is considerably reduced so that the desired protection of the transformer windings against damage from high voltage wave fronts is attained. The invention is also applicable without difficulty to high voltage windings of other apparatus such as choke coils.

We claim:

1. In a transformer of the concentric winding type, a high voltage winding comprising a plurality of disc-type coils arranged concentrically in superposed relation and connection in series to a high voltage lead-in and to form groups of coils, the connections between adjacent coils of the groups being made alternately at the radially

inner and outer sides of the coils, and a plurality of non-magnetic electrically conductive rings arranged in relatively close superposed relation at both the inner and outer sides of said coils, said rings being insulated each 5 from the other and being of such length along the axis of said high voltage winding as to capacitatively bridge adjacent coils at that inner and outer side of said high voltage winding at which said series-connected coils are without connection.

10 2. A high voltage winding as defined in claim 1 wherein the high voltage lead-in to said high voltage winding is connected to an end terminal of an endmost one of said 15 plurality of superposed disc type coils and wherein said conductive rings which lie at the inner and outer sides of said endmost coil are electrically interconnected and also connected to said high voltage lead-in.

3. A high voltage winding as defined in claim 1 wherein the high voltage lead-in to said high voltage winding is connected to an end terminal of an intermediate one of 20 said plurality of superposed disc type coils thereby to establish two branches in parallel extending in opposite directions from said intermediate coil.
